UNITED STATES PATENT OFFICE

157,868

HOSPITAL COMMODE

William S. Horn, Fort Worth, Tex.

Application November 26, 1948, Serial No. 149,841

Term of patent 14 years

(Cl. D4—5)

To all whom it may concern:

Be it known that I, William S. Horn, a citizen of the United States of America, residing at Fort Worth, in the county of Tarrant and State of Texas, have invented a new, original, and ornamental Design for a Hospital Commode, of which the following is a specification, reference being had to the accompanying drawing, forming part thereof.

I claim:
The ornamental design for a hospital commode, substantially as shown.

WILLIAM S. HORN.
